UNITED STATES PATENT OFFICE.

HENRY WEBER, OF CHICAGO, ILLINOIS, ASSIGNOR TO LATHAM MACHINERY COMPANY, OF CHICAGO, ILLINOIS, A CORPORATION OF ILLINOIS.

CUTTING MECHANISM FOR WIRE-STITCHING MACHINES.

1,071,121.

Specification of Letters Patent.

Patented Aug. 26, 1913.

Application filed August 16, 1911. Serial No. 644,373.

To all whom it may concern:

Be it known that I, HENRY WEBER, a citizen of the United States, residing at Chicago, in the county of Cook and State of Illinois, have invented certain new and useful Improvements in Cutting Mechanism for Wire-Stitching Machines, of which the following is a full, clear, and exact specification.

10 This invention relates to wire stitching or stapling machines, and the improvements have more especial reference to the means for cutting off the wire preparatory to forming the staple therefrom.

15 The invention has for its object to provide a wire cutter for the purpose described which shall be efficient in operation and of simple and durable construction.

20 The invention consists in the features of novelty described in the following specification and shown in the accompanying drawings forming a part thereof, and more particularly pointed out in the claims.

25 In the said drawings which show an example of the invention, Figure 1 is a face view of a part of a wire stitching machine embodying this invention; Fig. 2 is a vertical sectional view taken on the line 2—2 Fig. 1; Fig. 3 is a similar section taken on the line 3—3 Fig. 2; Fig. 4 is a detail plan sectional view taken on the line 4—4 Fig. 1; Fig. 5 is a detail perspective view of the cutter blade; and Fig. 6 is a detail perspective view of an arm hereinafter described.

30 As the wire comes from the wire feeding devices, well understood in this art and usually employed in connection with machines of this character, but which are not shown in this application, it passes through a suitable wire guide for holding it firmly while it is engaged by the cutter blade 7. In this example of the invention such guiding means is shown as a tube 8 arranged in the cutter block 9, suitably supported on frame 10, and having one face 11 adjacent the extremity of the guide tube 8. Against this face lies and slides the cutter 7, which is provided with suitable means for attachment to a shank 12, said means being here shown as a screw 13 passing through a hole 14 in the cutter blade, and having its inner extremity screw threaded in the stem 12. The cutter block 9 is provided with a socket 15 in which the stem 12 is housed and slides, the side of the socket being slotted out as

indicated at 16, through the face 11, for the passage of the screw 13. For convenience in manufacture both the socket 15 and shank 12 are made cylindrical. The upper end of the shank is connected to means for receiving motion from the usual cam shaft 17, or some other moving part of the machine for causing the cutter blade 7 to move across the end of the wire guide tube 8 and thereby sever the wire projecting there-through. For this purpose the end of the shank is formed with two flanges 18—19, which for convenience in manufacture may be cylindrical and turned up thereon or formed in any other suitable way, and between which flanges engages a bar or arm 20 arranged in a recess 21, which is formed in the upper end of the cutter block 9. This arm is secured to the end of a rod 22, in any suitable way, as for example by screw 23, or if desired it might be formed integrally therewith. The upper end of the rod 22 is arranged to be engaged at the proper time, by a cam 24 secured to cam shaft 17 or some other suitable moving part 80 of the machine, whereby the rod 22 will be depressed and the wire severed during each revolution of the cam shaft. To reduce friction the end of the rod 22 is provided with an antifriction roller 25, for the engagement of cam 24, and to facilitate and cheapen manufacture, the rod is made cylindrical so that its socket in which it is held and guided may be produced by a drill. This socket is formed in a frame part 26, or any other suitable support, which is also provided adjacent the rod 22, with a socket 27, parallel with the rod 22, and so close thereto as to constitute a slot between the two sockets for the passage of a pin 28, which is secured to the rod 22, and engages with one end of a spring 29 located in socket 27 for returning the rod 22 to its elevated position when released, by cam 24, this pin 28, by engaging in the slot between the two sockets, also constituting a means of holding the rod 22 against rotary movement.

When it is desired to remove the cutter blade for sharpening or for the substitution of a new blade, it is only necessary to remove the screw 30 which holds the cutter block 9 in place in the frame 10, thereby allowing the block to be withdrawn in an outward direction away from the arm 20, the recess 21 being open at the back as shown in Fig. 110.

3 to permit the block 9 to move outwardly without interference by the arm 20. It is also seen that with this construction the cutter block 9, together with the cutter blade 7, 5 may be adjusted back and forth with relation to the usual or any suitable staple forming and driving mechanism, ordinarily housed within frame member 31 notwithstanding the connection of the shank 12 with the rod 22 because, as is readily seen, the flanges 18—19 slide along such arm 20 during this adjustment without destroying the connection between the shank 12 and rod 22. This adjustment of the cutter block and 10 cutter blade may be effected in the usual or any suitable way. In the example of the invention shown in the drawings, the frame 10 is mounted on slide 32 in a slot 33 in the main frame member 34, and this slide is 15 suitably engaged by a rod 35 screw threaded in a support 36 on frame member 34, so that by the rotation of knob 37 the frame 10 will be adjusted with relation to frame 31 which houses the staple forming and driving devices. 20

25 I claim:

1. The combination with a wire seat, of a shank mounted adjacent to said wire seat, a cutter carried by said shank adapted to operate with said seat, a rod forming a continuation of said shank, and a connection between said rod and said shank whereby any movement imparted to said rod will likewise be imparted to said shank. 30

2. In a machine for the purpose described, the combination of means for supporting the wire preparatory to being cut, a cutter blade coöperating with said means for cutting the wire, a cutter block having a cylindrical socket slotted through the face of the block on one side, a cylindrical shank slidably mounted in said socket, means passing through said slot and connecting the cutter blade and shank together, a reciprocating rod, means detachably connecting said rod and shank together, and means for reciprocating said rod at the proper time to cut the wire. 40

3. In a machine for the purpose described, the combination of means for supporting the wire preparatory to being cut, a cutter blade coöperating with said means to cut the wire, a reciprocating shank to which said blade is secured and by which the blade is operated, a reciprocating rod operatively related to said shank for imparting reciprocating movement thereto and with relation to which rod said shank is adjustable in a direction transverse to its line of reciprocating movement, and means for reciprocating said rod at the proper time to sever the wire. 50

4. In a machine for the purpose described, the combination of means for supporting the wire preparatory to being cut, a cutter blade 60 coöperating with said means to cut the wire,

a shank to which said blade is secured and by which the blade is operated, and operating means for said shank, embodying an element extending transversely of the shank, and to which the shank is connected and 70 along which it is adjustable.

5. In a machine for the purpose described, the combination of means for supporting the wire preparatory to being cut, a cutter blade coöperating therewith for cutting the wire, a shank to which said blade is secured and by which the blade is operated, means for reciprocating the shank embodying an element extending transversely to the direction of reciprocation of the shank, said 75 shank having a flange engaging with said member and along which member said shank is adjustable, whereby the shank will be reciprocated by the member at various positions in the length of the latter. 80

6. In a machine for the purpose described, the combination of means for supporting the wire preparatory to being cut, a cutter blade coöperating therewith for cutting the wire, a shank to which said blade is secured 90 and by which the blade is operated, and means for reciprocating said shank embodying a reciprocatory rod operatively related to the shank, means for moving said rod in one direction, a spring supported in a position lengthwise of the rod, and a projection from the rod engaging one end of the spring for supporting the rod upon the spring. 95

7. In a machine for the purpose described, the combination of means for supporting the wire preparatory to being cut, a cutter blade coöperating therewith for cutting the wire, a shank secured to said blade, a cylindrical rod operatively related to the shank for reciprocating the same, a cylindrical socket in 100 which said rod is guided, a second socket extending lengthwise of said rod socket and having slotted communication therewith, a spring housed within said second socket, a projection extending from said rod through 105 said slot and resting upon said spring, and means for moving said rod against the action of said spring at the proper time to cut the wire. 110

8. In a machine for the purpose described, the combination of a cutter block provided with means for supporting the wire preparatory to being cut, a cutter blade, a reciprocating shank socketed within said block and secured to said blade, said block having a 115 recess, a horizontal arm in said recess to which said shank is detachably connected and along which the shank is adjustable in a direction transverse to the direction of reciprocation of the shank, a rod for moving said arm lengthwise of said shank, means for operating said rod, a frame adjustable 120 with relation to said rod, and means for detachably securing said cutter block to said frame. 125

9. The combination with a cutter block, of a wire seat carried thereby, a reciprocatory shank mounted for movement in said cutter block, a cutter carried by said shank for coöperation with said seat, an operating plunger rod coöoperating with said reciprocatory shank, and a detachable and positive connection between said plunger rod and said shank.
10. The combination with a cutter block, of a seat carried thereby, a reciprocatory shank mounted adjacent to said seat, a cutter element carried by said shank, means for reciprocating said shank, and an adjustable, detachable and positive connection between said shank and said means.
11. The combination with a wire seat, of a reciprocating member mounted adjacent thereto, a cutting element carried by said member, a means for reciprocating said member and the cutting element carried thereby, and a detachable, adjustable and positive connection between said means and said reciprocating member.
12. The combination with a cutter block, a seat carried thereby, a shank mounted for reciprocation in said cutter block, a cutting element carried by said shank, spaced flanges formed at the upper terminal of said shank,
- a driving rod mounted adjacent to said shank and adapted to operate the latter, and an elongated arm secured to the lower terminal of said driving rod and adapted to operate between said flanges.
13. The combination with a slide, of a cutter block carried thereby, a reciprocatory cutting mechanism carried by said cutter block, and means for operating said cutter mechanism irrespective of the position of said block and slide.
14. The combination with a slide, of a cutter block carried thereby, a reciprocatory cutting mechanism carried by said cutter block, means for operating said cutter mechanism, and a connection between said operating means and said cutter mechanism adapted to retain its operative position irrespective of the adjusted positions of the slide and cutter block.
- In testimony whereof I have signed my name to this specification, in the presence of two subscribing witnesses, on this 3rd day of August, A. D. 1911.

HENRY WEBER.
